United States Patent Office.

JOHN MURPHY, OF NEW YORK, N. Y.

Design No. 2,855, dated December 31, 1867.

DESIGN FOR A PISTOL-BARREL.

The Schedule referred to in these Letters Patent and making part of the same.

TO ALL WHOM IT MAY CONCERN:

Be it known that I, JOHN MURPHY, of the city and State of New York, have invented or produced a new and original Design for Pistol-Barrels; and I do hereby declare the following to be a correct description of the same, reference being had to the annexed drawing, making part of this specification, wherein—

Figure 1 is a plan or top view of the pistol and barrel, and

Figure 2 is an end view of the barrel.

My design relates to the shape and configuration of the metallic pistol-barrel.

The general exterior form of the under side *a* of the barrel *b* is semicircular, to fit into the stock, as now usual, but the sides of the upper part of the barrel are formed as rounding inclines *c*, extending from the semicircular part *a* to the edges of the longitudinal groove *d*, that runs along the top of the barrel, and in which is the sight *e*. The rear end of the groove *d* opens above the tail-piece *f* of the breech-pin, and the said breech-pin is rounded, as at *i*, to form the ornamental configuration at the said rear end of the groove *d*.

What I claim, and desire to secure by Letters Patent, is—

The design of the shape and configuration of the pistol-barrel with the grooved upper surface, as described, and shown in the drawings, within the lines *a*, *b*, *c*, and *d*.

In witness whereof, I have hereunto set my signature, this 16th day of November, 1867.

Witnesses:

CHAS. H. SMITH,

GEO. D. WALKER.

JOHN MURPHY.
